STAND FOR MUSIC OR THE LIKE

Martin E. Wrinkles, Jr., 1125 E. Gum St. 47714, and Carl R. Becker, 1153 E. Virginia St. 47711, both of Evansville, Ind.

Filed Aug. 22, 1966, Ser. No. 3,553

Term of patent 14 years

(Cl. D33—10)

FIG. 1 is a view in front elevation showing the applicants' new and novel claimed design for a stand for music or the like;

FIG. 2 is a view in side elevation of the claimed stand design of FIG. 1;

FIG. 3 is a view in rear elevation of the claimed stand design of FIGS. 1 and 2;

FIG. 4 is a top plan view of the applicants' new and novel design; and,

FIG. 5 is a view in perspective of the claimed stand design.

We claim:

The ornamental design for a stand for music or the like, as shown.
